UNITED STATES PATENT OFFICE.

WALTER M. LOWNEY, OF BOSTON, MASSACHUSETTS, ASSIGNOR TO THE
WALTER M. LOWNEY COMPANY, OF SAME PLACE.

DESIGN FOR A BONBON.

SPECIFICATION forming part of Design No. 23,400, dated June 26, 1894.

Application filed May 28, 1894. Serial No. 512,816. Term of patent 3½ years.

to all whom it may concern:

Be it known that I, WALTER M. LOWNEY, of Boston, county of Suffolk, and State of Massachusetts, have invented and produced a new and original Design for Use in the Manufacture of Candy, more especially of Chocolate Bonbons, of which the following is a specification, reference being had to the accompanying drawings, forming a part hereof.

Figure 1 is a perspective view from one corner of a piece of candy embodying my new design and Fig. 2 is a perspective view taken from another corner.

The leading feature of my design consists in the piece of candy in the shape of a rectangular prism, upon the top of which however, there is a slight projection running in two directions at right angles to each other and near two of the edges which join each other, each projection being continued down

two of what may be called the sides of the piece, and slightly irregular projections being formed where the straight projections cross each other, the whole being more simply described as representing a box wrapped in the manner indicated, with a piece of ribbon, the ends being tied to form a bow at the point where the two parts of the ribbon cross.

The projections representing the straight ribbons are indicated at A and B respectively, the bow being indicated at C.

What I claim is—

The design for a bonbon herein shown and described.

In testimony whereof I have hereunto set my hand this 17th day of May, 1894.

WALTER M. LOWNEY.
